DUPLICATING MACHINE

Charles H. Bratt, Groton, N. Y., assignor to L. C. Smith & Corona Typewriters, Inc., Syracuse, N. Y., a corporation of New York

Application December 17, 1942, Serial No. 469,337

12 Claims. (Cl. 101—132)

The invention relates to improvements in duplicating machines, and more particularly to that type of such machines employed for making copies by the liquid or spirit process of hectographic copying.

The principal objects of the invention are to provide in a duplicator of the liquid process type simple and efficient means for supporting a master and a master blocking-out element during copying operations and effecting relative adjustments therebetween at will for taking copies from the entire master or from different selected portions of the master; to provide in such a duplicator means for readily adjusting a block-out sheet or web relatively to a master mounted in the duplicator and holding said block-out sheet or web in the selected adjusted position thereof; to provide in such a duplicator means for adjusting independently a master and a block-out sheet or element for the master; to provide in such a duplicator efficient means whereby a long web of block-out paper or the like may be mounted in the duplicator and used as desired, and whereby successive portions of the web may be torn or cut off when necessary by reason of wear or otherwise; to provide for attainment of the above ends in a liquid process duplicator of the type in which the master and blocking-out element are carried by a rotary drum; and to provide means whereby the selected exposed area of the master may be contacted with a selected area of either a long or a short copy sheet.

Other objects and advantages of the invention will appear from the following detailed description of the several embodiments of the invention shown in the accompanying drawings.

In the drawings:

Figure 1 is a fragmentary side elevation of one form of duplicating machine embodying the invention, the machine being shown as viewed from its right hand side.

Figure 2 is a fragmentary vertical longitudinal sectional view taken medially of said machine.

Figure 3 is a detail view partly in section on the line 3—3 of Figure 1.

Figure 4 is a detail view showing in perspective parts of the driving means for one of the master clamping and adjusting rolls of the machine.

Figures 5 and 6 are fragmentary sectional views respectively taken approximately on the lines 5—5 and 6—6 of Figure 2, certain of the parts being broken away.

Figure 7 is a fragmentary face view of the master blocking-out sheet or web.

Figure 8 is a diagrammatic view showing a master sheet and a blocking out sheet or web held to the drum of the machine shown in Figures 1 to 6.

5 Figure 9 is a fragmentary sectional view taken approximately on the line 9—9 of Figure 11, with certain parts broken away, and showing a modified construction.

Figure 10 is a view similar to Figure 9 with certain parts omitted and showing more clearly a friction brake which bears on the spindle carrying the blocking web in the modified construction disclosed in Figures 9 to 12.

Figure 11 is a vertical transverse sectional view 15 taken substantially medially of the ends of the drum of the modified construction disclosed in Figures 9 to 12.

Figure 12 is a diagrammatic view showing a master sheet and a spool of blocking out web material held to the drum of the modified machine shown in Figures 9 to 11.

Figure 13 is a transverse sectional view taken substantially medially of the ends of a drum which may be substituted for either of those disclosed in the preceding views.

Figure 14 is a sectional view taken approximately on the line 14—14 of Figure 13.

Figure 15 is a view similar to Figure 13 showing another modification of the invention.

30 The embodiment of the invention shown in Figures 1 to 8 will first be described. The master and master blocking-out element carrier comprises a hollow drum 10 formed of metal or other suitably rigid material and fixed on an axial shaft 11. Shaft 11 is rotative in bearing sleeves 12 seated at the lower ends of vertical slots 13 formed in side walls 14 and 14^b which are parts of the stationary framework 14 of the machine. Drum 10 is removably held in the machine frame by two blocks 15 which are chan-

35 neled along their vertical side edges at 15^a to embrace said side walls along the edges of said slots 13 and are clamped to said walls by set screws 16 threaded in the blocks and bearing

40 sleeves 12 at their lower ends in channels 17 formed in and extending across the bearing sleeves 12 at the tops of the sleeves, thereby holding said sleeves against rotation.

45 The drum 10 is provided with a gap or slot 18 in its cylindrical wall, which gap extends longitudinally of the drum and parallel to the drum axis. In taking copies, the drum 10 is rotated counterclockwise as viewed in Figures 1 and 2 by any suitable hand or power driving means, such,

for example, as shown in United States patent to Flanigan, No. 2,185,188, January 2, 1940. The trailing longitudinal side edge wall of slot 18 preferably makes an obtuse angle with a tangent touching the drum periphery at said wall, and said edge wall preferably lies in a plane which is tangent to the peripheries of rolls 19 and 20 (hereinafter described) at the bight of this pair of rolls, as shown.

Mounted within drum 10, substantially opposite said gap 18 and close to the cylindrical path of the cylindrical drum wall, are a pair of master clamping and adjusting or feeding rolls 19-26 and a pair of blocking-out element clamping and adjusting or feeding rolls 21-22. The two pairs of rolls extend longitudinally of the drum parallel to the drum axis, and the bights of both pairs of rolls are opposite and close to gap 18 in the drum. These rolls may be formed of any suitable material, such as metal, and may be knurled or be faced with rubber, if desired.

Roll 19 is rotative about an axis fixed relatively to the drum, and roll 20 is spring-urged to roll 19. Roll 21 is rotative about an axis fixed relatively to the drum, and roll 22 is spring-urged to roll 21. At one end thereof, roll 19 is journaled on a pivot screw 23 threaded through an end portion of the drum, and roll 21 is similarly journaled at one end thereof on a pivot screw 24 threaded through an end portion of the drum. Rolls 19 and 21 are rotatively supported at their other ends by shouldered shafts 25 and 26, respectively. Each shaft 25 and 26 is rotatively journaled in an end portion of the drum. Shaft 25 has a finger wheel 27 detachably fixed thereon exteriorly of the drum, and shaft 26 has a finger wheel 30 similarly fixed thereon exteriorly of the drum, said finger wheels being located at opposite ends of the drum. Each shaft has a reduced inner end portion of square cross-section releasably engaged in a socket of similar cross-section in the adjacent end of the roll supported thereby to afford a supporting and driving connection 6 between each shaft and the corresponding roll.

For each of the rolls 20 and 22 there is provided a pair of supporting arms (arms 28 for roll 20, and arms 29 for roll 22), each arm formed with a hub. Shouldered pivot screws 9 extend through the hubs of arms 28, and similar pivot screws 8 extend through the hubs of arms 29, said screws being threaded in end portions of the drum and extending parallel to the drum axis. The rolls 19 and 21 are intermediate the rolls 20 and 22, and each arm 28 is connected to the arm 29 adjacent the same end of the drum by one of two contractile coiled springs 7 to urge roll 20 to roll 19 and roll 22 to roll 21.

A platen or counterpressure roll 30 is suitably journaled on the framework of the machine below the drum for coaction with drum 10 to feed a moistened copy sheet rearwardly between the platen and drum in pressure contact with a master carried by the drum for taking copies from the master. The mounting of the platen is preferably that disclosed in said Flanigan patent.

While various means may be provided for delivering the copy sheets one at a time rearward into the bight of the drum and platen, the means shown (which is substantially like that of said Flanigan patent, except as hereinafter pointed out) is preferred. Said means will now be briefly described, and reference may be had to said patent for a more detailed disclosure of said means.

Clear copy sheets are fed into the machine

from a feed table 31 fixed on the framework 14. Such sheets are introduced one at a time between a pair of introductory feed rolls 32-33 against sheet stop means 34 while roll 32 is lifted away from roll 33 and the sheet stop means 34 is in stopping position, i. e. while the parts are positioned as shown in Figures 1 and 2. Preferably a plurality of the stops 34 is provided as in said Flanigan patent. Rolls 32-33 have registering annular grooves 32a-33a to receive the forward end of each such stop 34. A supply of hectograph ink solvent is maintained by suitable means in a trough 35 mounted in the framework. A roll 36 turning in said trough contacts a roll 37 which receives solvent from roll 36 and applies solvent to the upper face of a copy sheet as the latter is fed between roll 37 and an underlying counter-pressure roll 38, said rolls being suitably journaled in the framework. A spring 39 normally pivots the stop device 34 to sheet stopping position about a rock shaft 40 which is journaled in the walls 14a-14b and forms part of a rocking frame 40-47. Roll 32 is journaled in a rocking frame 41 journaled in walls 14a-14b, and a spring 42 acts on said frame to normally press roll 32 down toward roll 33. A lever 43, fulcrumed on the framework at 44, has one arm thereof engaged under a tappet 45 on frame 41 and under a tappet 46 on the rocking frame 40-47 to cause movement of sheet stop 34 out of stopping position and simultaneous lowering of roll 32 into contact with roll 33 once during each revolution of the drum 10. The other arm of lever 43 has thereon a cam follower 48 engaged under the periphery of a rotative cam disk 49 normally held to the drum shaft 11 to rotate with the drum.

Preferably, the timing cam disk 49 is rotatively adjustable through a complete circle relatively to the drum by means similar to that shown in my application for United States patent Serial No. 435,383, filed March 19, 1942. This means comprises a collar 50 fixed on drum shaft 11 and against which the cam disk and the inner end of the hub 51 thereof are clamped by means of a nut 52. Nut 52 is threaded on a reduced end portion of the shaft 11 and presses against the outer end of hub 51 a resilient metal disk 53 which is pinned to shaft 11. When the nut is loosened, the cam and its hub can be rotated relatively to the drum 10 and shaft 11 and disk 53 through a complete revolution. By tightening the nut, the cam is held to rotate in unison with the drum. An annular row of graduations 54 is provided on the outer face of the cam hub 51 and a coactive graduation 55 is provided on the outer face of disk 53 to facilitate setting of the timing cam.

Suitable driving gearing (not shown), arranged as in the Flanigan patent above referred to, positively rotates the drum in the direction indicated by arrows on the drawings in taking copies, and positively drives rolls 33, 36 and 38 clockwise as viewed in Figure 2 during rotation of the drum.

In the embodiment of the invention shown in Figures 1 to 8, and described above, one end or edge of the flexible hectographic master sheet or web 56 is inserted into the drum 10 through gap 18 and between the rolls 19 and 20, and the remainder of the master sheet, or so much thereof as is desired and determined by feeding of the sheet into the drum by said rolls, is left outside of the drum to trail partly or entirely around the drum behind said gap for backing of said remainder of the master by the periphery of the

drum. The blocking out sheet or web 57 of suitable material, such as paper, may be either imperforate or may be provided with apertures or windows 58 of selected sizes and shapes for exposing parts of the master through the blocking out sheet. The blocking out sheet is inserted at one end thereof through gap 18 and between rolls 21 and 22, and so much of said blocking out sheet as is desired may be left to trail around the drum over the drum-backed portion of the master sheet.

By feeding actuation of the rolls 19-20 the master may be variably fed into and out of the drum independently of the blocking out sheet, and the latter sheet may be variably fed into and out of the drum independently of the master by feeding actuation of rolls 21-22. The blocking out sheet may be readily detached and may be fed far enough into the drum to expose the entire copyable portion of the master. Any width of master sheet or blocking out sheet, or both, within the limit of the length of the gap 18 may be employed. By using one or more blocking out sheets more narrow than the master sheet, different widthwise portions or columns of the master may be blocked out.

In the embodiment of the invention shown in Figures 9 to 12, the drum 10^a and parts thereon is provided to be substituted for the drum 10 in the machine above described. The drum 10^a has a gap 18^a corresponding to gap 18 of drum 10 and has mounted therein a pair of master clamping and feeding rolls 19^a and 20^a corresponding to rolls 19-20 in drum 10. The mountings of rolls 19^a and 20^a are the same as those of rolls 19-20 in drum 10, roll 19^a having connected thereto a finger wheel 21^a corresponding to finger wheel 21. Contractile coil springs 7^a urge roll 20^a to roll 19^a. Drum 10^a differs from drum 10 in that there is substituted for the pair of blocking out sheet clamping and feed rolls 21-22 a spindle 59 for a roll of blocking out material 66, and an idler guide roll 60 for the web of material rolled on the spindle. The guide roll 60 is journaled within the drum at the opposite side of roll 19^a from roll 20^a, being journaled on pivot screws 61 threaded in the drum. Said roll 60 and spindle 59 extend longitudinally of the drum opposite gap 18^a. Spindle 59 is journaled at one end on a pivot screw 63 threaded through an end portion of the drum, and is rotatively supported at its other end by a shouldered shaft element 62 which rotates with the spindle and has a reduced end portion extending through and journaled in an end portion of the drum. A finger wheel 64 is detachably fixed on said reduced end portion of shaft 62 externally of the drum. The spindle is provided with a narrow longitudinal slot 65 for detachable anchorage of one end of a long web of blocking out material 66 to the spindle. The material is trained from the spindle over idler roll 60, and thence through gap 18^a and over the master sheet 56^a for blocking out purposes. By converse rotations of the spindle, the web 66 may be rolled upon and unwound from the spindle.

In the third embodiment of the invention, shown in Figures 13 and 14, the drum 10^b and parts thereon are provided for substitution for drum 10 in the machine shown in Figures 1 to 6 and 8. Drum 10^b is provided with an idler guide roll 60^b and spindle 59^b, constructed and mounted as is the case with roll 60 and spindle 59 in drum 10^a, opposite gap 18^b in the drum. Spindle 59^b is provided with a finger wheel 64^b, and with a

slot 65^b for attachment of a roll of blocking out material to the spindle for reeling thereon and unreeeling therefrom. On drum 10^b there is substituted for the master clamping and feeding means of drums 10 and 10^a a master clamping means located just behind gap 18^b, which means will now be described.

The master clamping means on drum 10^b comprises a row of clamping pins 67, said pins reciprocable radially of the drum and arranged in a row extending longitudinally of the drum. The pins are slidably guided in holes in the cylindrical wall of the drum and in holes in an internal bar 68 within and fixed to the drum. Each pin has a lip for engaging over the leading end of a master sheet to clamp the master sheet to the drum. A bar 79 is countersunk in the drum and underlies lips 69 of all the pins 67. A coiled expansion spring 70 surrounds each pin between bar 68 and a suitable abutment 76 on the pin to urge lip 69 to clamping position. The entire row of pins is movable outwardly to release the master by means of a rod 71 carried by rock arms 72 fixed on a rock shaft 73 journaled in end portions of the drum. An operating handle 74 is fixed on one end of shaft 73 externally of the drum. A return stop pin 75 on the drum limits return movement of handle 74. Parts 71 to 14 are returned by torsion springs 77 engaged with the arms 72 and the drum. Any other suitable means for releasably holding a master by its leading end to the drum may be substituted for that above described.

In the fourth embodiment of the invention shown in Figure 15, the drum 10^c and parts thereon are provided for substitution for drum 10 in the machine shown in Figures 1 to 8. Drum 10^c is provided with master clamping means constructed like that on drum 10^b and including parts 67^c-70^c-71^c-72^c-73^c-77^c-79^c to clamp a master sheet, but is provided with a pair of blocking out sheet clamping and feeding rolls 21^c-22^c constructed and mounted as is the case with rolls 21-22 in drum 10. Said rolls are mounted opposite a gap 18^c in drum 10^c, which gap is located slightly in advance of the master clamping means and corresponds to gap 18 of drum 10, for clamping and feeding of a blocking out sheet by said rolls. Pull springs 7^c urge roll 22^c to roll 21^c, and roll 21^c has a finger wheel 80^a connected therewith similarly to wheel 80 for roll 21 of drum 10 in the first described embodiment of the invention.

In those embodiments of the invention wherein a spindle for a roll of blocking out material is provided, a suitable means may be provided for insuring against possible accidental rotation of the spindle. Such a means is shown in Figure 10 and comprises a spring arm 76 fixed at one end to the drum at 78 and pressing adjacent the free end of the arm against spindle shaft 62 to provide a friction brake for the spindle.

It will be obvious that in those embodiments of the invention in which the drum carries a roll or spool of blocking out material, the web of such material may be many times as long as the circumference of the drum, and that, from time to time, as successive free end portions of said web become unsuitable for use, the worn end portion may be cut or torn off and the next succeeding portion of the web used for blocking out purposes.

It will be noted that in various embodiments of the invention the blocking out material is variably extensible or feedable around the drum periphery, and that in certain embodiments of the invention provision is made for variable feeding

of the master into and out of the drum. It will also be noted that the embodiments of the invention shown provide means for effecting relative adjustments between the master and a blocking out element.

I claim:

1. In a liquid process duplicator, the combination of means for backing and holding a master for taking of copies therefrom, and means for supporting a roll of blocking out material for variable unreeling of said roll of material over a master held and backed by the first-mentioned means.

2. In a rotary duplicating machine of the liquid process type, the combination of a drum and an opposed counter pressure roll rotative to feed a copy sheet therebetween in pressure contact with a master carried by the drum, said drum having a gap therein extending longitudinally thereof, means for holding a master to the drum with at least a part of the master extending about the periphery of the drum and backed thereby for taking of copies therefrom, and means for variably feeding a flexible block-out element through said gap over a master held to the drum and for holding said element in different fed positions to rotate with the drum.

3. In a rotary duplicating machine of the liquid process type, the combination of a drum and an opposed counter pressure roll rotative to feed a copy sheet therebetween in pressure contact with a master carried by the drum, said drum having means for carrying a roll of block-out material for unreeling thereof variably at will around the periphery of the drum, and means for holding a master to the drum for variable coverage of the master by the block-out material.

4. In a rotary duplicating machine of the liquid process type, the combination of a drum and an opposed counter pressure roll rotative to feed a copy sheet therebetween in pressure contact with a master carried by the drum, said drum having a gap therein extending longitudinally thereof, means on said drum for holding a flexible master to the drum and operable at will to feed the master variably into and out of the drum through said gap, and means on said drum for holding a flexible block-out element to the drum and operable at will to feed the block-out element variably into and out of the drum through said gap.

5. A master and block-out element carrying means for a rotary duplicator of the liquid process type comprising a drum having a gap therein extending longitudinally thereof, a pair of master clamping and adjusting rolls carried by said drum within the drum opposite said gap and extending longitudinally of the drum, manually operable means at one end of the drum for actuating said rolls to adjust a flexible master through said gap, a pair of block-out element clamping and adjusting rolls carried by said drum within the drum opposite said gap and extending longitudinally of the drum, and manually operable means at one end of the drum for actuating said block-out element clamping and adjusting rolls to adjust a flexible block-out element through said gap.

6. A master and block-out element carrying means for a rotary duplicator of the liquid process type comprising a drum having a gap therein extending longitudinally thereof, a pair of master clamping and adjusting rolls carried by and within the drum and extending longitudinally of the drum adjacent said gap, manually operable means at one end of the drum for actuating said rolls to adjust a flexible master through said gap, a spindle for a roll of flexible block-

out material carried by and within the drum adjacent said gap, and means at one end of the drum for rotating said spindle to adjust through said gap block-out material wound on said spindle.

7. Master and block-out element carrying means for a duplicator of the liquid process type comprising a drum having a gap therein extending longitudinally thereof, means carried by the drum for fixedly clamping one end of a flexible master to said drum adjacent said gap with the master backed by the periphery of the drum, and means for supporting a roll of flexible block-out material within the drum adjacent said gap for variable unreeling of said material through said gap to cover selected parts of a master clamped by said clamping means.

8. Master and block-out element carrying means for a duplicator of the liquid process type comprising a drum having a gap therein extending longitudinally thereof, means carried by the drum for fixedly clamping one end of a flexible master to the drum with the master backed by the periphery of the drum, a pair of clamping and adjusting rolls carried by and within the drum adjacent said gap for reception therebetween of a flexible blocking out element for the master extending through said gap, and means at one end of the drum for actuating said rolls to variably adjust such blocking out element through said gap.

9. In a liquid process duplicating machine, the combination of a rotatively mounted drum having a gap therein extending longitudinally thereof, a pressure roll coactive with the drum, said drum being rotative in one direction to feed a copy sheet between the drum and pressure roll for taking a copy from a master backed and carried by the drum, copy sheet feeding and moistening means variably settable for delivery of one moistened copy sheet into the bight of the drum and pressure roll per revolution of the drum and at a time when said gap is located at any selected point around the axis of the drum, and a spool of flexible blocking-out material carried by and within the drum adjacent said gap with said spool extending longitudinally of the drum for variable unreeling of said material at will through said gap.

10. Master carrying and blocking out means for a rotary duplicator of the liquid process type comprising, in combination, a drum having a gap therein extending longitudinally thereof, two pairs of rolls carried by the drum within the drum and extending longitudinally of the drum substantially opposite said gap, means supporting one roll of each pair for rotation about a fixed axis, independent means for each of the last-mentioned rolls manually operable at will to rotate said rolls independently of each other, independent shiftable supporting means mounted on the drum journaling the remaining two rolls for bodily movement of the latter independently toward and from their companion rolls, and a resilient means connecting the shiftable supporting means for the bodily movable rolls to constantly urge each said roll to its companion roll, said pairs of rolls being adapted to clamp respectively a master and a block-out sheet therefor and being operable independently to feed a clamped master and a clamped block-out sheet through the gap in the drum.

11. Master carrying and blocking out means for a rotary duplicator of the liquid process type comprising, in combination, a drum having a gap

therein extending longitudinally thereof, means for holding a master to said drum for backing of the master by the drum, a pair or rotative rolls carried by and within the drum adjacent said gap and extending longitudinally of the drum, means for yieldingly urging said rolls to each other to clamp a block-out sheet extending through said gap in the drum, and means operable at will to actuate said rolls for variable feeding into and out of the drum of a block-out sheet clamped by said rolls.

12. A rotary duplicator having a master element backing drum and means to hold a master element to rotate with the drum with at least

5 a portion of said master element backed by the periphery of the drum with a copyable face of said backed portion of the master element exposed for the taking of copies therefrom, the combination with said drum and said master element holding means of means to adjustably project and retract a blocking out element over the exposed face of the backed portion of the master element circumferentially of the drum to vary 10 the linear extent to which said blocking out element will overlap said exposed face of the backed portion of the master element circumferentially of the drum.

CHARLES H. BRADT.
